ATTY.

UNITED STATES PATENT OFFICE.

WILLIAM J. KELLY, OF JAMAICA, NEW YORK

DOOR-STOP.

1,338,571.

Specification of Letters Patent. Patented Apr. 27, 1920.

Application filed April 18, 1919. Serial No. 291,025.

To all whom it may concern:

Be it known that I, WILLIAM J. KELLY, a citizen of the United States, residing at Jamaica, in the county of Queens and State 5 of New York, have invented new and useful Improvements in Door-Stops, of which the following is a specification.

This invention relates to door stops and has particular reference to a means which 10 may be adapted for use in connection with any door closing device or check, in order to retain the door in an open position.

In the ordinary form of door stops the same are usually arranged at the bottom of 15 the door and contact with the floor for retaining the same in an open position, but as such arrangement has been found to have many disadvantages one of the principal objects of this invention is to overcome these 20 objections by arranging the door stop means at the top of the door frame, in an out of the way position.

Another object of the invention is the provision of a device of the class described 25 which is entirely automatic in operation, whereby the same is rendered operative for retaining the door in an open position, by swinging the door in predetermined distances and which is as readily rendered inoperative by the ordinary force required to 30 close the door.

A still further object of the invention is the provision of a device of the class described which is of simple construction, inexpensive to manufacture and which is 35 easily installed.

With these and other objects in view the invention resides in the novel construction, combination and arrangement of parts more 40 fully described and pointed out in the following description and claims and illustrated in the accompanying drawings in which:

Figure 1 is a fragmentary view of a door-way showing the door stop applied and holding the door in an open position.

Fig. 2 is a horizontal sectional view on the line 2—2 of Fig. 1.

Referring to the drawings A designates a 50 door frame provided with a door B which is hinged to the frame as shown at C. The frame is provided with the usual top bar D which acts as a limit for the closing of the door. The door stop comprises a link 55 10 which is pivoted by means of a bolt 11 to the bifurcated lug 12 on the base plate 13

which is secured adjacent the upper portion of the door B by means of screws or the like. A cotter pin 14 is passed through the bolt 11 whereby the link may be readily disconnected from the lug 12 when it is desired to remove the stop. The link 10 is slotted as at 15 for the major portion of its length and the inner end of said slotted portion communicates with an enlarged opening 16 for a purpose to be hereinafter described. The outer extremity of the link 10 has secured to its under side a spring finger 16 which is provided with an embracing portion 17 and an outturned lip 18. Secured to the under face to the top bar D is a base member 19 which is provided with a downwardly extending spherical head 20 having a reduced neck 21 which engages with the slotted portion 15 of the link and 60 guides the same in its movement. It will thus be seen that while the device is intended primarily to retain the door in an open position, it is also utilized as a means for preventing the door from contacting with the wall and it is therefore a substitute for the ordinary base board stops which are 65 now in use.

In operation of the device when the door is swung to the position shown in the drawings the embracing portion 17 of the finger 16 engages and co-acts with the head 20 to retain the door in an open position. In the ordinary opening of the door the device will not operate to hold the same in its open position due to the fact that the inner secured portion of the end of the embracing portion of the spring 16 co-acts with the link 10 to project the head past the lip 18 and when it is desired to render the stop active in order to retain the door in its open position it is necessary to open the same and hold it momentarily in order to properly position the head within the embracing portion 17. When it is desired to disengage the head 20 from the embracing portion in order to close the door, the usual power necessary in closing a door is applied and the finger 15 will spring over the head 20 allowing the member to assume the position shown in dotted lines of Fig. 2 of the drawing. Upon the opening of the door to the required distance to render the stop active the head 20 will contact with the out-turned lip 18 which acts as a cam to flex the finger 16 sufficiently 105 to allow the head to enter the embracing portion 17. By removing the cotter pin 14 110

and the bolt 11 the link 15 may be moved to a position to register the opening 16 with the head 20 thus allowing the removal of the link 10.

5 While the link is shown as pivoted to the door and the head as provided on the frame it will be understood that a reverse arrangement of the devices may be resorted to if desired.

10 From the foregoing description taken in connection with the accompanying drawings it will be seen that I have described and shown a preferred form of carrying my invention into practice, but I do not care to be limited to the exact details therein exhibited and reserve the right to make such changes and alterations as fall within the scope of the appended claims.

What is claimed as new is:

20 1. A device for retaining a swinging door in open position comprising a link removably pivoted to said door, a slotted portion in said link, a head depending from the door frame and provided with a reduced neck 25 adapted to engage with said slotted portion, and a spring finger provided with an embracing portion and an out-turned lip adapted to co-operate with the head for retaining the door in an open position.

30 2. A door stop comprising a link adapted to be pivotally supported by the door, a plate adapted to be secured to the door frame and provided with a depending shank having a spherical head, a spring finger secured to 35 the free terminal of the link and provided with an embracing portion adapted to accommodate the spherical head, said finger also having an out turned lip curved away from the embracing portion, the link having a slot 40 freely receiving the shank and co-acting therewith to maintain said link between the head and the plate and serving to guide the lip over the head to position the embracing portion thereover or remove the same therefrom.

45 3. A device of the class described comprising a link adapted to be pivotally supported by a door, a shank adapted to be fixedly supported to the door frame, the link 50 having a slot therein freely receiving the shank thereon, a spherical head formed on the shank and positioned at one side of the link so as to underlie the slot and support the link, and a spring secured to one end of 55 the link and having a free terminal adjacent to one end of the slot curved to conform

with said spherical head and curved away from the link to provide a spring deflecting surface adapted to contact with said head to permit the latter to enter the curved portion of said terminal, the slot positioned to permit the head to be guided in order to maintain operative co-acting relation between the head and the spring.

60 4. A device of the class described comprising a link adapted to be pivoted at one end to a door and having a slot therein, a base plate adapted to be fixedly secured to the door frame, a spherical head, a reduced neck connecting the latter with the base plate, the slot of said link freely receiving the reduced neck to guide the link in its movements between the base plate and the spherical head, a spring finger secured to the free extremity of the link and having an 65 outwardly bowed portion adapted to directly overlie the outer extremity of the slot and constituting an embracing portion for the reception of the spherical head when the latter registers with the outer extremity 70 of the slot, the free extremity of the bowed portion engaging the link and having an out-turned lip constituting an entering mouth to receive the head.

75 5. A device of the class described comprising a link adapted to be pivoted at one end to a door and having a slot therein, a base plate adapted to be fixedly secured to the door frame, a spherical head, a reduced neck connecting the latter with the base plate, the 80 slot of said link freely receiving the reduced neck to guide the link in its movements between the base plate and the spherical head, a spring finger secured to the free extremity of the link and having an outwardly bowed portion adapted to directly overlie the outer extremity of the slot and constituting an embracing portion for the reception of the spherical head when the latter registers with the outer extremity of the 85 slot, the free extremity of the bowed portion engaging the link and having an out-turned lip constituting an entering mouth to receive the head, the opposite extremity of the bowed portion of the finger being adapted 90 to co-act with the link to serve as means for forcibly projecting the head from the embracing portion as and for the purpose specified.

95 In testimony whereof I affix my signature. 100

105 WILLIAM J. KELLY,
